SPOON OR SIMILAR ARTICLE OF FLATWARE

Marion Weeber, New York, N. Y., assignor to National Silver Company, New York, N. Y., a corporation of New York

Application April 23, 1956, Serial No. 41,174

Term of patent 14 years

(Cl. D54—12)

FIG. 1

Fig. 1 is a plan view of a spoon embodying my new design.

Fig. 2 is an edge view showing the configuration of the spoon as seen from the side.

The essential features of the design reside in the portions shown in full lines in the drawing.

The back of the spoon is substantially plain.

I claim:

The ornamental design for a spoon or similar article of flatware, as shown and described.
